2 Claims. (Cl. 230—101)

ABSTRACT OF THE DISCLOSURE

A four stage diffusion pump including four jet assemblies mounted one above the other, each jet assembly being circular and having a uniform annular mouth gap. The width of the second jet assembly mouth gap is 0.9 to 1.3 times the width of the first or bottom jet assembly mouth gap; the width of the third jet assembly mouth gap is 0.5 to 0.9 times the width of the first jet assembly mouth gap; and the width of the fourth or top jet assembly mouth gap is 0.4 to 0.6 times the width of the first jet assembly mouth gap. The diameter of the second jet assembly mouth gap is 0.88 to 0.92 times the diameter of the first jet assembly mouth gap; the diameter of the third jet assembly mouth gap is 0.55 to 0.62 times the diameter of the first jet assembly mouth gap; and the diameter of the fourth jet assembly mouth gap is 0.28 to 0.30 times the diameter of the first jet assembly mouth gap. The distance between the second and third jet assembly nozzle lips is 1.0 to 4.0 times the distance between the first and second jet assembly nozzle lips; and the distance between the third and fourth jet assembly nozzle lips is 1.0 to 4.0 times the distance between the first and second jet assembly nozzle lips.

This invention relates generally to diffusion vacuum pump apparatus and more particularly to four-stage diffusion vacuum pump apparatus.

The operation of high vacuum diffusion pumps is generally well known. A suitable pumping fluid (typically oil) is evaporated in a heated boiler of the pump and the resulting vapor is directed at supersonic velocity through a nozzle system to be condensed on a cold surface. As the high speed vapor stream passes between the nozzle system and the condensing surface, it accepts by diffusion gas molecules from the chamber being evacuated and compresses them into a higher pressure region which normally communicates with a mechanical backing pump. The liquid condensate formed on the condensing surface returns to the pump boiler for reheating and re-evaporation.

Since the conception of the vacuum diffusion pump periodic efforts have been made to improve such pump characteristics as pumping speed, gas throughput capacity, attainable ultimate pressure, etc. Although some improvements have been made in these areas a need has continued to exist for a vacuum diffusion pump possessing significantly improved performance characteristics.

The object of this invention therefore is to provide a diffusion vacuum pump which exhibits significantly improved pumping performance characteristics.

One feature of this invention is the provision in a multi-stage diffusion vacuum pump of four vertically stacked jet assemblies which have critically interrelated dimensions so as to produce in combination highly improved performance characteristics.

Another feature of this invention is the provision of a diffusion vacuum pump of the above featured type wherein in each of the four jet assemblies possesses a uniform annular mouth gap adapted to direct pumping fluid vapor against the interior surface of the pump housing and

2

wherein the width of the second jet assembly mouth gap is 0.9–1.3 times the width of the bottom jet assembly mouth gap, the width of the third jet assembly mouth gap is 0.5–0.9 times the width of the bottom jet assembly mouth gap and the width of the top jet assembly mouth gap is 0.4–0.6 times the width of the bottom jet assembly mouth gap.

Another feature of this invention is the provision of a diffusion vacuum pump of the above featured types wherein in the jet assembly mouth gaps are circular and wherein the diameter of the second jet assembly mouth gap is 0.88–0.92 times the diameter of the bottom jet assembly mouth gap, the diameter of the third jet assembly mouth gap is 0.55–0.62 times the diameter of the bottom jet assembly mouth gap and the diameter of the top jet assembly mouth gap is 0.28–0.3 times the diameter of the bottom jet assembly mouth gap.

Another feature of this invention is the provision of a diffusion vacuum pump of the above featured types wherein in the jet assemblies have substantially horizontal nozzle lips and wherein the distance between the second and third jet assembly nozzle lips is 1.0–4.0 times the distance between the bottom and second jet assembly nozzle lips and the distance between the third and top jet assembly nozzle lips is 1.0–4.0 times the distance between the bottom and the second jet assembly nozzle lips.

Another feature of this invention is the provision of a diffusion vacuum pump of the next above featured types wherein each of the jet assemblies has a substantially horizontal nozzle lip and wherein the distance between the second and third jet assembly nozzle lips is 1.2–3.2 times the distance between the bottom and second jet assembly nozzle lips and the distance between the third and top jet assembly nozzle lips is between 1.7–3.7 times the distance between the bottom and second jet assembly nozzle lips.

These and other objects and features of this invention will become more apparent upon a perusal of the following specification taken in conjunction with the accompanying drawing which is a partial cross sectional view of a preferred invention embodiment.

Referring now to the drawing there is shown the diffusion vacuum pump 11 having a cylindrical pump housing 12. The flanged inlet aperture 13 at the top of the pump housing 12 is adapted for connection with a vacuum chamber (not shown) to be evacuated. The flanged exhaust tubulation 14 communicates with the lower portion of the pump housing 12 and is adapted for connection to a conventional mechanical forepump (not shown). The boiler section 15 located in the lower portion of the pump housing 12 is adapted to contain a suitable pumping fluid, for example oil. The hollow cooling coil 16 is attached in intimate contact with the outer surface of the pump housing 12 and is adapted for connection to a source of cooling fluid (not shown).

Resting on the bottom of the pump housing 12 and adapted to extend above the pumping fluid pool is the hollow cylindrical pump base 17. Supported from the pump base 17 are the vertically stacked first and bottom jet assembly 21, second jet assembly 22, third jet assembly 23, and fourth and top jet assembly 24. The bottom jet assembly 21 is formed by the hollow cylindrical lower jet portion 25 which extends directly out of the pump base 17 and includes the central support column 26 attached by radial brackets 27. The top jet portion 28 includes the hollow cylinder 30 which extends into the lower jet portion 25 and is separated therefrom by a uniform annular space 29. The upper jet portion 28 also includes a projection 31 which extends over the upper edge of the lower jet portion 25 and is separated therefrom by the circular mouth gap 32. The projection 31

terminates in a substantially horizontal nozzle lip 33 which encircles the lower cylindrical jet portion 25. The radial mounting brackets 34 attach the upper jet portion 28 to the central support column 35 which is supported by and coaxial with the central support column 26.

Extending above and integral with the top jet portion 28 is the hollow cylindrical lower jet portion 36 of the second stage jet assembly 22. The upper portion 37 of the second stage jet assembly 22 is constructed and supported in the same manner as the upper portion 28 of the first stage jet assembly 21 to form the second stage mouth gap 38. Similarly the third stage jet assembly 23 includes the top jet portion 39 which forms the third stage mouth gap 41.

The fourth stage jet assembly 24 includes the inverted cup-shaped cover portion 42 which extends over the upper jet portion of the third stage jet assembly 24. The cover portion 42 is supported by a central column and forms the fourth stage mouth gap 43.

During operation of the diffusion pump 11 the pumping fluid contained in the pump boiler section 15 is heated by a suitable heating device (not shown) and the resulting pumping fluid vapor rises through the hollow cylindrical jet assemblies. A portion of the rising vapor passes through the annular space 29 and is directed through the first stage mouth gap 32 downwardly against the cooled interior surface of the pump housing 12. This vapor condenses and returns to the pump boiler section 15. Similarly, other portions of the pumping fluid vapor are directed against the inner surface of the pump housing 12 by the second stage jet assembly 22, the third stage jet assembly 23 and the fourth stage jet assembly 24. While passing between the jet assemblies and the pump wall the high speed vapor accepts by diffusion gas molecules coming from a chamber (not shown) connected for gas communication with the inlet aperture 13. These gas molecules are compressed into the lower portion of the pump housing 12 and removed through the exhaust tubulation 14 by a conventional mechanical fore-pump (not shown) connected thereto.

In attempting to obtain optimum performance for the diffusion pump 11 it was found that a critical interrelationship exists between certain dimensions of the individual jet assemblies. For example, optimum performance was obtained only if the width w_2 of second stage gap 38 was 0.9-1.3 times the width w_1 of the first stage gap 32, the width w_3 of the third stage gap 41 was equal to 0.5-0.9 times w_1 and the width w_4 of the fourth stage gap 43 was equal to 0.4-0.6 times w_1 . The terms w_1 , w_2 , w_3 and w_4 represent the minimum gap widths existing between the upper and lower jet portions of the individual jet assemblies.

Similarly, it was found that the relative diameters of the jet assembly mouth gaps were extremely critical. For example, optimum performance was obtained only with the diameter d_2 of second stage jet assembly 22 equal to 0.88-0.92 times the diameter d_1 of first stage jet assembly 21, the diameter d_3 of the third jet assembly 23 equal to 0.55-0.62 times d_1 and the diameter d_4 of the fourth stage jet assembly 24 equal to 0.28-0.3 times d_1 .

Also found to be critical were the relative vertical distances between the individual jet assemblies. Thus, for good pump performance the distance L_{23} between the nozzle lips of the second stage jet assembly 22 and the third stage jet assembly 23 should be between 1.0-4.0 times the distance L_{12} between the nozzle lips of first stage jet assembly 21 and second stage jet assembly 22 and the distance L_{34} between the nozzle lips of the third stage jet assembly 23 and fourth stage jet assembly 24 should be between 1.0-4.0 times L_{12} . For even better pump performance the distance L_{23} should be between 1.2-3.2 times L_{12} and L_{34} should be between 1.7-3.7 times L_{12} .

A vacuum diffusion pump built in accordance with the critical range of interrelated dimensions illustrated above

will exhibit greatly improved performance characteristics. It is important to note that the critical range of dimension given are not limited to pumps of one size. The relationship was found to exist for pumps of various sizes and capacities.

Obviously, many modifications and variations of the present invention are possible in light of the above teachings. It is, therefore, to be understood that within the scope of the appended claims the invention may be practiced otherwise than as specifically described.

What is claimed is:

1. A diffusion vacuum pump apparatus comprising: a pump housing having an inlet aperture adapted to receive pumped gas and an outlet aperture adapted to exhaust pumped gas, a boiler section formed within said pump housing and adapted to contain a pool of pumping fluid, a first jet assembly positioned within said pump housing above said boiler section and adapted to receive a portion of the pumping fluid vapor evaporated therefrom, a second jet assembly mounted above said first jet assembly and adapted to receive a portion of the pumping fluid vapor evaporated from said boiler section, a third jet assembly mounted above said second jet assembly and adapted to receive a portion of the pumping fluid vapor evaporated from said boiler section, a fourth jet assembly mounted above said third jet assembly and adapted to receive a portion of the pumping fluid vapor evaporated from said boiler section;

each of said jet assemblies having a uniform annular mouth gap and being adapted to direct pumping fluid vapor through said mouth gap against the interior surface of said pump housing, the width of said second jet assembly mouth gap being 0.9-1.3 times the width of said first jet assembly mouth gap, the width of said third jet assembly mouth gap being 0.5-0.9 times the width of said first jet assembly mouth gap, and the width of said fourth jet assembly mouth gap being 0.4-0.6 times the width of said first jet assembly mouth gap;

said jet assembly mouth gaps being circular and the diameter of said second jet assembly mouth gap being 0.88-0.92 times the diameter of said first jet assembly mouth gap, the diameter of said third jet assembly mouth gap being 0.55-0.62 times the diameter of said first jet assembly mouth gap, and the diameter of said fourth jet assembly mouth gap being 0.28-0.3 times the diameter of said first jet assembly mouth gap; and

each of said jet assemblies having a nozzle lip, the distance between said second and third jet assembly nozzle lips being 1.2-3.2 times the distance between said first and second jet assembly nozzle lips, and the distance between said third and fourth jet assembly nozzle lips being 1.7-3.7 the distance between said first and second jet assembly nozzle lips.

2. A diffusion vacuum pump apparatus comprising: a pump housing having an inlet aperture adapted to receive pumped gas and an outlet aperture adapted to exhaust pumped gas, a boiler section formed within said pump housing and adapted to contain a pool of pumping fluid, a first jet assembly positioned within said pump housing above said boiler section and adapted to receive a portion of the pumping fluid vapor evaporated therefrom, a second jet assembly mounted above said first jet assembly and adapted to receive a portion of the pumping fluid vapor evaporated from said boiler section, a third jet assembly mounted above said second jet assembly and adapted to receive a portion of the pumping fluid vapor evaporated from said boiler section, a fourth jet assembly mounted above said third jet assembly and adapted to receive a portion of the pumping fluid vapor evaporated from said boiler section,

and

each of said jet assemblies having a nozzle lip, the distance between said second and third jet assembly nozzle lips being 1.2-3.2 times the distance between said first and second jet assembly nozzle lips.

pumping fluid vapor evaporated from said boiler section;
 each of said jet assemblies having a uniform annular mouth gap and being adapted to direct pumping fluid vapor through said mouth gap against the interior surface of said pump housing, the width of said second jet assembly mouth gap being 0.9-1.3 times the width of said first jet assembly mouth gap, the width of said third jet assembly mouth gap being 0.5-0.9 times the width of said first jet assembly mouth gap, and the width of said fourth jet assembly gap being 0.4-0.6 times the width of said first jet assembly mouth gap;
 10 said jet assembly mouth gaps being circular and the diameter of said second jet assembly mouth gap being 0.88-0.92 times the diameter of said first jet assembly mouth gap, the diameter of said third jet assembly mouth gap being 0.55-0.62 times the diameter of said first jet assembly mouth gap, and the diameter of said fourth jet assembly mouth gap being 0.28-0.3 times the diameter of said first jet assembly mouth gap;

15

and each of said jet assemblies having a nozzle lip, the distance between said second and third jet assembly nozzle lips being 1.0-4.0 times the distance between said first and second jet assembly nozzle lips, and the distance between said third and fourth jet assembly nozzle lips being 1.0-4.0 the distance between said first and second jet assembly nozzle lips.
